[57] CLAIM

The ornamental design for a licorice strip or similar article, as shown and described.

DESCRIPTION

FIG. 1 is a top perspective view of a licorice strip or similar article showing my new design;

FIG. 2 is a bottom perspective view thereof;

FIG. 3 is a front elevational view thereof; and

FIG. 4 is a right side elevational view thereof.

In rear elevation and in left side elevation, the licorice strip or similar article has the appearance respectively depicted in FIGS. 3 and 4.
